UNITED STATES PATENT OFFICE

JOHN H. WARE, JR., OF OXFORD, PENNSYLVANIA

DISPLAY BOX

Application filed January 23, 1931. Serial No. 510,758.

The subject of my invention is to provide a display device adapted to contain a plurality of packages arranged in steps. My display device has side walls which may be generally diagonal in outline so that two such boxes may be fitted together or superposed to present a rectangular outer surface adapted to fit in a rectangular container for shipment.

At the taller end of my box there is provided a flap which has a bendable portion thereon adapted to display printed matter when in upright position and it may extend for more than the width of a package when bent parallel to the bottom of the box. My display device is also provided with tabs struck from the side walls of the box at such a height as to engage the package which forms the second step, or higher like step if present, and to thereby retain that package in position and it also helps friction to retain packages which form the lower layer in position. My display device also has its lower end bent over and fastened to the bottom to reinforce the box at that point.

For a further exposition of my invention reference may be had to the annexed drawings and specification at the end whereof my invention will be specifically pointed out and claimed.

In the drawings,

Figure 1 is a view in projection showing two of my display devices nested or fitted together.

Figure 2 is a view in projection showing my display device with packages arranged in steps.

Figure 3 is a side elevation with parts broken away.

Figure 4 is a vertical cross section looking to the left of Figure 3.

Figure 5 is a view in projection showing one type, selected from other types, of packages adapted to be displayed in my device.

Figure 6 is a view in projection showing my display device with the flap in upright position.

Figure 7 is a side elevation showing two of my display devices fitted together.

Figure 8 is a diagrammatic view showing the blank from which the box is made.

In the embodiment chosen for illustration in the drawings and referring especially for convenience to Figure 6 there is therein disclosed a display device consisting essentially of a box generally indicated at 1 which is adapted to contain a plurality of packages 2 arranged in steps. Box 1 is adapted to nest with a similar box so that both boxes together present a rectangular outer surface which may be contained in a rectangular package for shipment with the packages in place. Upon arrival at the retail store or other ultimate sales point this outer container is opened and the two display devices are removed and separated. The flaps are then bent to upright position whereupon the device is in position to display the goods without further adjustment.

Box 1 has a bottom wall generally indicated at 3 and side walls 4 and 5 which are generally diagonal in outline. As seen in Figure 3 the box 1 contains a plurality of packages 2 and walls 4 and 5 may be notched or otherwise cut to fit the packages which are arranged in steps.

The taller end of the box is reinforced by means of a portion 66 which is adapted to be bent down parallel to the end wall. Between the end wall and the flap 66 there are located flaps 67 and 68 which form extensions of the side walls 4 and 5 and which serve to reinforce this end of the box.

At the taller end of the box 1 is located a flap 6 which is fastened to bottom 3 by means of a tab 7 struck from bottom 3. Flap 6 may however be fastened to the box in any convenient manner. At its upper end flap 6 has a bendable portion 8 which may be bent into a position parallel to the bottom of the box so that grasping the display device with the thumb or fingers resting on the portion 8, one may retain all the packages in the box. Portion 8 is adapted to display printed matter on its inner face when in upright position.

From the central portion of side walls 4 and 5 there are struck tabs 9 of which the number is appropriate to number of tiers

of packages employed. These may be of any desirable shape. As shown, these tabs are located at a convenient height to engage the package 2 which forms the second step 5 and in the case of more steps than shown, additional tabs are provided and arranged to engage additional and superposed packages. As shown most clearly in Figure 4 tab 9 is intended to be slid into package 2.

10 The wall 11 which forms the lower end of box 1 is bent over against itself and flattened out against the bottom 3 of the box where it is retained by a tab 12 or by any other convenient means. Flap 11 therefore serves to 15 reinforce this wall of the box.

From the foregoing it is believed apparent that a person may slide two boxes apart from the position shown in Figure 1 and by holding the flap 8 down with the thumb or 20 fingers all the packages 2 may be retained in box 1 arranged in steps in an attractive position for display. Flap 8 is then simply bent to upright position where it displays the printed matter on its inner face and 25 serves to carry out the step arrangement of the packages in a very attractive manner.

I do not intend to be limited in the practice of my invention save as the scope of the prior art and of the attached claims may 30 require.

I claim:

1. A display device comprising a box having side walls generally diagonal in outline defining a normally open upper surface and 35 adapted to contain a plurality of packages arranged in steps and adapted to fit with a similar box so that both boxes present a rectangular outer surface and tabs struck from the said side walls of the box at a sufficient 40 height to engage a package resting on another package.

2. A package rectangular in form and comprising, in combination, two separate open top boxes adapted for face to face assembly and each higher at one end than it is at the other end and each provided at its high end with a flap and at its side wall with a tab, and packages filling said boxes and arranged in adjacent groups of progressively increasing number from the low to the high ends of the boxes, an intermediate group of packages being held in the boxes by the tabs, and a group of packages at the high end being held in the boxes by said flaps.

3. The combination of an open top box higher at one end than it is at the other end and provided at the high end with a flap and at its side with a tab, and stepped packages filling the box and whereof the packages at the high end are retained in the box by the flap and the packages at the intermediate portion are retained in the box by the tab, the tops of the sides of the box 65 extending from the low end of the box to

the front of the top package at the high end of the box.

4. A display device comprising a box having one end higher than the other, a plurality of packages covering the bottom wall of said box, additional packages arranged on said first mentioned packages and on each other in stepped relation, the end wall of said box at the lower end being of a height equal to the height of one of the packages, and the end wall at the higher portion of said box being of a height which is approximately a multiple of the height of one of said packages, the side walls of said box having a portion equal in height to said higher end wall and extending the distance of the width of one of said packages, and said side walls of said box having a portion cut away diagonally from said higher height to said lower height, whereby said box and the packages therein may interfit detachably with a similar box and packages to form an object rectangular in outline.
